UNITED STATES PATENT OFFICE

109,789

DESIGN FOR A CLOSURE ATTACHMENT FOR A PITCHER OR SIMILAR ARTICLE

Ralph H. Pershall, Bremerton, Wash., assignor
to Sanicut Mfg. Co., Port Orchard, Wash., a
corporation of Washington

Application June 14, 1937, Serial No. 69,837

Term of patent 14 years

To all whom it may concern:

Be it known that I, Ralph H. Pershall, a citizen
of the United States, residing at Bremerton, in
the county of Kitsap and State of Washington,
have invented a new, original, and ornamental
Design for a Closure Attachment for a Pitcher
or Similar Article, of which the following is a
specification, reference being had to the accom-
panying drawing, forming part thereof.

Figure 1 is a perspective view of the closure
attachment for a pitcher or similar article show-
ing my design; and

Figure 2 is a top plan view thereof.

I claim:—

The ornamental design for a closure attach-
ment for a pitcher or similar article, as shown.

RALPH H. PERSHALL.
